UNITED STATES PATENT OFFICE.

STANLEY W. WIDNEY, OF CHICAGO, ILLINOIS.

PEDAL ATTACHMENT.

1,132,057.

Specification of Letters Patent. Patented Mar. 16, 1915.

Application filed June 22, 1912. Serial No. 705,226.

To all whom it may concern:

Be it known that I, STANLEY W. WIDNEY, a citizen of the United States, residing in the city of Chicago, in the county of Cook and State of Illinois, have invented certain new and useful Improvements in Pedal Attachments, of which the following is a specification.

This invention relates to improvements in 10 pedal attachments for pianos and the like and has among its salient objects to provide novel and improved means for closing the openings in the toe rail through which the pedals extend to prevent mice or other 15 vermin entering the piano at this point and at the same time in no way interferes with the freedom of movement of the pedal shanks; to provide in a construction of the character referred to, an improved form of 20 mouse guard which can be readily attached to the standard types of pedal shanks and is adapted to move bodily with the latter; to provide a construction in which the mouse 25 guard is seated at the inner side of the toe rail so as to be substantially concealed from view; to provide simple and yet effective spring supports for the pedal bars and in which the latter are firmly locked against lateral or longitudinal movement relative to 30 the spring supports, and without the use of bolts, screws, or other extraneous fastening devices; to provide a construction in which the spring supports are so connected to the 35 pedal bars that depression of the latter automatically increases the effective tension of the springs; to provide a spring support of the above character which is more particularly adapted for use with wooden or metal pedal bars and in general to provide 40 simple and improved means of the character referred to.

The invention consists in the matters hereinafter described and more particularly pointed out in the appended claim.

45 In the drawings—Figure 1 is a perspective view of a piano pedal action equipped with my invention; Fig. 2 is a fragmentary vertical sectional view of the same; Fig. 3 is a fragmentary view, partly in section and partly in side elevation and showing more particularly the construction of the mouse guard; Fig. 4 is a fragmentary

side elevation of one of the pedal bars; Fig. 5 is a perspective view of one of the spring supports for such bars.

55

Referring to the drawings—1 designates the base or bottom of the piano case and 2 the toe rail, which is suitably apertured to receive the pedal shanks 3, 3 of the respective pedals 4, 4. In the present instance the pedal shanks 3 are of an inverted channel shape as shown in cross section in Fig. 3. The inner ends of these pedals are pivoted as shown at 5 to suitable brackets or mountings 6, fastened as shown 60 at 7 to the base 1. To each of the pedal shanks is connected a lifter rod or pedal prop 8, the upper end of which is secured as shown at 9 to corresponding pedal bars 10. As shown more clearly in Figs. 2 and 70 3, the apertures 2' in the toe rail are considerably larger than the cross section of the pedal shanks 3, in order to permit of the depression of the pedal.

To prevent mice or other vermin from 75 entering the piano through the openings in the toe rail for the pedals below the shanks of the latter, various forms of mouse guards have heretofore been devised. Some of these mouse guards have been particularly 80 adapted to peculiar types of pedal shanks and others have been bent around or over the shank of the pedal. These mouse guards however, have for one reason or another been objectionable from a commercial stand- 85 point. None of them as far as I am aware combines the simplicity and effectiveness of my invention.

Referring in particular to Figs. 2 and 3, my improved form of mouse guard comprises a flat metal plate 11, provided at its upper end with a reduced extension or tongue 12, which fits in the channel of the shank 3 and terminates in a right angled extension or lip 13, which is secured by a 90 screw 14 and a nut 15 to the under side of the shank 3. The guards are preferably secured to the shanks 3 just inside of the toe rail 2 and when the pedals are depressed the guards enter the slot or channel 16 cut in the 100 face of the base or bottom board 1. It will be noted that the slot 16 and the main body of the guard 11 are inclined downwardly and inwardly so that the guards will not in-

terfere with the free movement of the pedals as the latter swing upon their pivots when they are depressed or carried downwardly.

The construction just described is such

5 that it effectively prevents any mice from entering the piano and further that the guard is rigidly locked against displacement without in any way interfering with the pedal action.

10 Referring now to the manner of supporting the pedal bars 10, which forms one feature of the present invention the lower end of each of these bars is provided with a downwardly and forwardly inclined slot 17, 15 adapted to receive the upper end 18 of the curved supporting spring 19. Each of these springs is formed of a flat single piece of spring steel, the lower end of which is secured at 20, 21 to the base 1, the upper end 20 of which is notched as shown at 22 to form ears 23. These ears 23 fit over the opposite sides of the corresponding pedal bars 10 as shown clearly in Fig. 1. The construction is such that the pedal bars are detachably yet 25 effectively locked against lateral movement independent of their spring supports. In addition the arrangement just described increases the effective action of the springs. As the pedal is depressed the inner end of 30 its pedal bar is carried downwardly and the slotted portions of the bar tightly grip the upper end of the spring thus giving the desired tension to the spring support. It is obvious that the pedal bars may be readily

connected to or detached from their springs 35 while at the same time there is no danger of the bars working loose from their spring supports.

I am aware that numerous devices of 40 spring supports have been heretofore devised but none of them obtain the effectiveness of the present invention.

The invention is not limited to the details of construction shown except as set forth in the appended claim. 45

I claim as my invention:

In a piano pedal attachment, the combination with a base member, a toe rail therefor having a pedal opening, a pedal having a shank extending through said opening, said shank being of inverted channel shape in cross section, a pivotal support for the inner end of said shank, a mouse guard at the inner end of said opening comprising a flat plate of comparatively thin sheet metal provided at its upper end with an angularly bent tongue secured to the under side of said shank and fitting into the channel thereof, and a bolt extending through said shank and tongue securing said parts together, the main body of said guard being inclined inwardly toward said support, and said base having a similarly inclined slot to receive said guard when the pedal is depressed. 55
